DUDLEY B. HOWARD, OF WASHINGTON, DISTRICT OF COLUMBIA

MARKSMANSHIP-TRAINING DEVICE FOR FIREARMS

Application filed October 8, 1929. Serial No. 398,168.

(GRANTED UNDER THE ACT OF MARCH 3, 1883, AS AMENDED APRIL 30, 1928; 370 O. G. 757)

The invention described herein may be manufactured and used by or for the Government for governmental purposes, without the payment to me of any royalty thereon.

The invention relates to training devices 5 for use in instruction practice with firearms, and in particular to means for overcoming "trigger jerking" and "flinching."

In firing a rifle, pistol, or other small-arm, 10 properly, the trigger must be squeezed gradually and with perfect control while endeavoring to maintain the sights aligned on the target. Otherwise, the aim will be deranged at the instant of discharge. The majority of beginners experience an irresistible 15 impulse to "jerk" the trigger quickly through its entire path of movement without proper coordination of the trigger manipulation with the aiming. Erratic marksmanship is the result of this simple "trigger jerking." 20 Whenever the aim happens to be correct or nearly so, at the time of discharge a "bull's-eye" or fairly close hit is obtained. A good hit is often preceded and followed by wild shots. This is not expert shooting.

The cause of "trigger-jerking" is believed 25 to be increased psycho-motor tension. The most readily recognizable evidence of this cause is not the improper trigger manipulation, but rather the hurried firing of a series 30 of shots. The interval between shots is too brief. The instructor experiences great difficulty in forcing a person who is suspected 35 of trigger-jerking to pause between shots long enough to study the pattern of hits on the target and to compute corrections in aiming, holding, etc., necessary to improve the results. While diagnosis of the trouble is rendered easy and certain by this symptom, 40 selection of a remedy is a serious problem. The method of feeding the ammunition to the firer round by round as needed and preceding issue of each cartridge by calm advice, intended to reduce the state of tension, 45 has been tried with indifferent success.

An aggravation of the tendency to "jerk" the trigger is the malady known as "flinching," which is commonly associated with gun-shyness. The "flincher" convulsively contracts the firearm-holding muscles as well 50 as those of the trigger finger. The aim is positively deranged, as distinguished from inability on the part of most marksmen to hold steadily without slight swaying, which is normal. Flinching results in a greater 55 percentage of wild shots than the less serious "trigger jerking."

A person who flinches when firing with "live" ammunition may not display any 60 signs of flinching when practicing aiming and trigger-squeezing without ammunition. Likewise he may not flinch when actually firing with low-caliber ammunition that does not cause the weapon to "kick." This proves 65 that flinching is the unsuppressed muscular reaction produced by fear stimuli. When firing a high-power weapon for the first time, the fear is one of personal danger. After experience has shown the danger to be negligible the original reaction persists unless 70 suppressed by the use of will power.

The worst harm that can result from firing 75 a high-powered rifle for instance, will be a bruised shoulder and deafened ears. A small proud class of men scoff at such injuries and refuse to pad their shoulders or to put cotton in their ears. They "steel their nerves," so to speak, and fire without flinching. The great majority, however, flinch 80 badly under such conditions and even continue to do so when protected by the means just mentioned.

The recoil of a high-powered rifle or pistol 85 causes it to jump to such a degree that flinching is obscured. The convulsive muscular reactions of the firer are difficult of detection by others and the firer himself may not realize just what he is doing. He may blame the innocent rifle or the wind for his erratic shooting.

Marksmanship instructors have had to devise means for detecting and exposing the flinching of such persons. By watching the eye of the firer, it is often possible to observe tell-tale contraction of the eyelids immediately preceding discharge of the firearm. Convincing the firer that he displayed symptoms of flinching is another problem. The common method of accomplishing this has been to insert an unloaded "dummy" cartridge surreptitiously into a clip of ammunition which is about to be used by the unsuspecting firer. One or more live cartridges are fired with possible flinching obscured by recoil. Then, the "dummy" reaches the chamber of the firearm and fails to fire when the trigger is manipulated. If the firer flinches, the firearm will be jerked out of properly aimed position very noticeably. The firer and any other person who may be observing his reactions will have undeniable proof of flinching.

Although quite effective, exposure of flinching by trickery is objectionable. The firer, who suddenly finds that he has been tricked into "making a fool of himself", is almost certain to be resentful. He will also be on his guard against any further attempts to prove his flinching. It may be possible to break that man of his bad habit, but more time will be spent than if it had been possible to convince him of that habit by "above board" methods.

It is the object of the present invention to provide a simple mechanical attachment for firearms which is capable of being used to expose flinching with previous knowledge on the part of the firer that it is a device for that purpose. He may know before he attempts to fire that he is undergoing a flinching test. At the same time, he is powerless to out-guess the device. It is up to him to exert such muscular control that any tendency to flinch will be suppressed.

A further object is to produce an instrument of this nature which will aid in the development of proper control in holding and firing by calling into play natural habit-breaking metal processes. It is adapted to be used with high-power ammunition. The usual fear-producing stimuli will be present and the use of will-power will be required, but the instrument stimulates unusual effort at control because of the knowledge that any flinching reactions will surely be exposed. Appeal is made to personal pride. Furthermore, the rate of fire will be regulated. Firing cannot be faster than the instrument will permit. This check is especially useful in alleviating psycho-motor tension.

The invention will be more fully understood when the following specific description is read in connection with the accompanying drawings, in which:—

Figure 1 is a side elevation of an automatic pistol showing one form of the flinch-breaker attached thereto:

Figure 2 is a plan view:

Figure 3 is a rear elevation of this form of the device:

Figure 4 is a vertical sectional view of the same showing the locking member in inoperative position:

Figure 5 is a horizontal section of the same:

Figure 6 is a vertical section through a modified pneumatic form of the device; and

Figure 7 is an enlarged fragmentary view of the stem and adjusting key.

The drawings show the inventive idea in its reduction to practice as an attachment for automatic pistols of a well known type. In adapting the invention to other kinds of firearms, such as revolvers, rifles, etc., variations in the details of constructions may have to be made. Regardless of this consideration, the device, which for the sake of brevity will be termed "flinch-breaker", may be analyzed into certain essential elements which will in all probability be present in any embodiment or adaptation. These elements are, broadly speaking, a blocking member, a lock for the blocking member, an adjusting key for the lock, and a shield for the lock to prevent visual inspection of the condition of the lock and blocking member. This assembly of elements is intended to be combined with two parts common to all firearms. These are the firing mechanism and the frame.

If the device is to be in the form of an external attachment, which is at the present time considered to be preferable for reasons of safety and interchangeable use on various firearms of the same type, that part of the firing mechanism which will be utilized will probably be the hammer, "cocking-piece" or equivalent member. If the invention should be built into the firearm, some other suitable movable part of the firing mechanism may be utilized instead. In the specification and claims, the term "firing member" will be used to designate any suitable part of the firing mechanism as a whole, which moves during operation of discharging the firearm and which, if obstructed or locked, will prevent such discharge.

The term "frame member" will be used hereinafter to mean some suitable part of the firearm which is held substantially stationary with the barrel during operation of the firing mechanism in firing at a target. Such a frame member may be the slide of the automatic pistol, the frame of a revolver, or the stock or barrel breech of a rifle.

In the illustrative embodiment of the invention an attaching member 1 is adapted to be clamped on the slide 2 of the pistol as a support for the blocking member 3, which is mounted on a pivot disposed intermediate of its extremities. One end of the blocking mem-

ber is disposed in the path of movement of the pistol hammer and should be beveled as at 5 in order that the hammer may deflect it out of the way to permit firing when the blocking member is not locked against movement by means which will now be described.

A hollow shield 6 is supported by the attaching member, or clamp, 1. This shield may be in the cylindrical form shown to fit the lock or "chance device," as it may be termed, which is circular in cross section. Shield 6 has a slot 7 through which the end of blocking member 3 opposite to the end which is adapted to be disposed in the path of the firing member may extend into the interior thereof.

Referring particularly to Figures 4 and 5, a convenient form of lock is disclosed. This lock consists of a slotted disc 8 attached to a rotatable stem 9. The stem is axially disposed in the cylindrical shield and has its lower end journaled in the bearing 10. The upper end of the stem is shown extending through a central opening 11 in a removable cover 12 for the shield. The protruding upper end of the stem 9 should be cylindrical in form in order that the position of the lock will not be revealed, as might be the case if the stem were of any other cross-section. A cylindrical socket 9a is provided in this upper end of the stem and has a transverse key slot 9b in its bottom. An adjusting key 13 is adapted to fit the socket in the lock stem. This key is preferably in the form of a flywheel with a central, cylindrical shank matching the lock stem in size. A reduced portion 13a fits the socket 9a and has a transverse spline 9b adapted to engage the key slot 9b. The shoulder on the key shank, which is a function of the reduction of portion 13a, will rest on the upper end of the lock stem when the key is in use and thereby aid the shield 6 in completely masking the condition of the lock. The flywheel construction facilitates manipulation of the key to spin the lock on its axis and gives added momentum to the lock to increase the duration of its spinning.

It will be noted that the lock disc 8 has a plurality of pairs of opposed slots 14. This arrangement of slots results in a well balanced spinning lock. The width of each slot should exceed the width of the inwardly projecting end of blocking member 3 in order to permit free movement of the latter through any slot which may happen to be disposed in registration with the slot 7 in shield 6 when the lock is at rest. The lock disc should be located on stem 9 immediately below the inner end of the blocking member when the latter is in its normal position of rest with its inner end bearing against the cover 12 of the shield. The blocking member is maintained in this position due to the fact that it is unbalanced, the end portion which projects across the path of the firing member

being heavier than the opposite, inner end portion. It should be apparent that the lock is adapted to obstruct downward movement of the inner end of blocking member 3 when a solid portion of the disc happens to be in registration with the slot in the shield, whereas such movement of the blocking member will be permitted when one of the disc slots is in a similar position. In accordance with the purpose of the invention, it is desirable that the chances of the blocking member being either obstructed by the lock or free to rock on its pivot, when the disc has come to rest after being spun, shall be equal. For that reason the total area of the disc slots in a horizontal plane should be equal to the total area of the solid disc portions.

The operation of the device will now be described. Assuming that an instructor in marksmanship suspects flinching on the part of some particular firer in pistol practice, he clamps the flinch breaker on the pistol slide in the position shown in Figure 1, preferably while the pistol is not loaded. In this position, the outer end of the blocking member will rest on top of the hammer when the latter is in its forward, firing position, provided the lock of the flinch breaker is in such a position that the inner end of the blocking member is projecting into one of the disc slots. The firer is then required to load the pistol, which includes pulling the slide back to cause insertion of one cartridge into the chamber. During rearward motion of the slide, the blocking member will return to its normal position of rest when the hammer has been cocked. The lock may now be set in an indeterminate position by spinning the flywheel. The instructor may do this himself, but it may be more effective to require the firer to perform this operation, because any resulting exposure of flinching and the attendant embarrassment will be due to the firer's own act. There can be no resentment toward the instructor. When the lock ceases to spin of its own accord, or is stopped by grasping the fly wheel with the fingers, the lock will be in one of its two conditions. It will either lock the blocking member or permit free movement of the same. Neither the instructor nor the firer can determine the condition of the lock from the external appearance of the instrument. If the lock is set to obstruct movement of the blocking member the hammer of the pistol will be checked by the blocking member when the trigger is squeezed and the pistol will not fire. On the other hand, if the lock is in its inoperative condition, the blocking member will be deflected by the hammer and the pistol will fire. This state of uncertainty presents a problem to the firer which causes him to pause and do a little thinking before attempting to squeeze the trigger. The gun may fire. If it should do that, it will kick

and make a loud report. The thought of that gives him the impulse to jerk the trigger quickly and have it over with, but he realizes that, if the gun happens to be locked against firing, such hasty manipulation of the trigger and other possible exaggerated contraction of the pistol-holding muscles will cause the whole pistol to be jerked out of proper aiming position. Such "flinching" will be noticed by the instructor and any other bystanders and will prove that he is unable to control his muscles. If he has any personal pride he will not want to show such lack of control. Therefore, he will be distinctly "on his mettle" and will try hard to suppress his usual reactions. He will try to squeeze the trigger slowly and gradually while maintaining the sights aimed at the target. He may be able to complete the trigger squeezing properly the first time. Usually, the tendency to jerk and flinch will assail him in the midst of his trigger squeezing. He may make a desperate effort to regain control by releasing the trigger and starting all over again with his trigger squeezing. However, he may not be able to overcome the impulse and may flinch. Should the gun happen to fire, his flinching may be obscured. If the gun is prevented from firing there will be a tell-tale indication of flinching which the firer cannot deny. The firer should be required to use the flinch-breaker until he has proven that proper control has been regained. In such use, the device will assist the instructor in the exercise of strict fire discipline. In fact, a flincher who is honest with himself can make use of the flinch-breaker voluntarily as a means for subjecting himself to fire discipline without making it necessary for an instructor to work with him. The device should prove to be most efficacious under such self-enforced use, for the firer will have the right mental attitude from the start.

The flinch-breaker lends itself to other uses in instruction practice with small arms, such as putting the brake on the tendency toward hurried firing on the part of men who do not actually flinch but could shoot better if they were more deliberate and careful. Such uses should be apparent to persons skilled in the art to which it pertains.

A modified form of lock for the flinch breaker is disclosed in Figure 6. Instead of having a slotted disc, the disc 15 is solid throughout and forms a piston movable within the cylinder 16 formed by the shield. The piston is longitudinally slidable on the spinning stem 17. The cylinder has a plurality of air vents 18 in its bottom wall and a valve plate with ports 20 adapted to register with the vents 18 is attached fixedly to the stem 17 in close proximity to the bottom of the cylinder. A spring 21 interposed between the piston and the valve plate serves to maintain the piston normally in contact with the

blocking member 22 when the latter is in its normal position of rest. To prevent undue friction in the spinning of the stem, the piston 15 and the valve plate 19 should fit loosely within the cylinder so that practically all of the friction is in the bearings for the stem.

The operation of this pneumatic form of the invention is as follows: When the lock stem has been spun in the usual manner and has come to rest, the bottom portion of the cylinder will either be open to the atmosphere or closed by the valve 19. If the valve should be closed, the firing member, upon striking the blocking member, will cause the inner end of the latter to exert pressure on the piston and this pressure will be resisted by compression of the air beneath the piston. The gun will fail to fire. If the piston and valve plate happen to fit very loosely within the cylinder, there may be slow and gradual leakage of air past the edges of these parts which will result in slow lowering of the firing member of the weapon to its inoperative position. This action is not objectionable. On the other hand, if the valve is open, depression of the piston will be freely permitted, due to the rapid expulsion of air through the valve ports, and the gun will fire.

In either form of the invention, the removable cover for the cylindrical shield serves an additional purpose. Being screw-threaded in its engagement with the shield, it is capable of vertical adjustment. The cover therefore serves as convenient means for precision adjustment of the blocking member angularly on its pivot to bring the beveled end into proper vertical relation to the path of movement of the firing member.

In adapting the invention to various types of fire arms and in improving and simplifying its construction for any type of fire arm, obvious modifications may be made without departing from the essential principles disclosed herein and covered by the appended claims.

I claim:

1. The combination with a firearm including a firing member, of means for locking the firing member against firing movement, means for shielding the locking means to conceal the operative condition thereof, and an adjusting member for the locking means, the adjusting member being of a construction and movable mounting to conceal changes in adjustment.

2. In a device of the class described, an attaching member for engagement with the frame of the firearm, a blocking member movably mounted on the attaching member and adapted when secured against movement to block firing operation of the firing member and a lock for the blocking member including a movable member having solid portions separated by slots and adapted to be adjusted to bring solid portions and slots alternately

into the path of movement of the blocking member to obstruct movement of the blocking member and permit free movement of the same respectively.

5. In a device of the class described, an attaching member for engagement with the frame of the firearm, a blocking member movably mounted on the attaching member and adapted when secured against movement to block firing operation of the firing member, a lock for the blocking member including a movable member having solid portions separated by slots and adapted to be adjusted to bring solid portions and slots alternately into the path of movement of the blocking member to obstruct movement of the blocking member and permit free movement of the same respectively, and means for adjusting the lock member.

10. In a device of the class described, an attaching member for engagement with the frame of the firearm, a blocking member movably mounted on the attaching member and adapted when secured against movement to block firing operation of the firing member, a lock for the blocking member including a movable member having solid portions separated by slots and adapted to be adjusted to bring solid portions and slots alternately into the path of movement of the blocking member to obstruct movement of the blocking member and permit free movement of the same respectively, and means for shielding the lock member to conceal its adjusted position.

15. In a device of the class described, an attaching member for engagement with the frame of a firearm, a blocking member movably mounted on the attaching member and adapted when secured against movement to block firing operation of the firing member, and a lock including a rotary member having a portion adapted to be brought into position to obstruct movement of the blocking member, a shield enclosing the lock to conceal the operative condition thereof from external view, and means for rotating the lock member.

20. In a device of the class described, an attaching member for engagement with the frame of a firearm, a blocking member movably mounted on the attaching member and adapted when secured against movement to block firing operation of the firing member, and a lock including a rotary member having a portion adapted to be brought into position to obstruct movement of the blocking member, a shield enclosing the lock to conceal the operative condition thereof from external view, and a rotatable operating stem of circular cross-section for the lock member projecting exteriorly from the shield.

25. In a device of the class described, an attaching member for engagement with the frame of a firearm, a blocking member movably mounted on the attaching member and

adapted when secured against movement to block firing operation of the firing member, and a lock including a rotary member having a portion adapted to be brought into position to obstruct movement of the blocking member, a shield enclosing the lock to conceal the operative condition thereof from external view, a rotatable operating stem of circular cross-section for the lock member projecting exteriorly from the shield, the operating stem having a key socket in its outer end, and a manipulating key of circular cross-section having an axial stem portion with a reduced end formed to fit the key socket in the operating stem for the lock member.

30. In a device of the class described, an attaching member for engagement with the frame of a firearm, a blocking member movably mounted on the attaching member and adapted when secured against movement to block firing operation of the firing member, and a lock including a rotary member having a portion adapted to be brought into position to obstruct movement of the blocking member, a shield enclosing the lock to conceal the operative condition thereof from external view, a rotatable operating stem of circular cross-section for the lock member projecting exteriorly from the shield, the operating stem having a key socket in its outer end, a manipulating key of circular cross-section having an axial stem portion with a reduced end formed to fit the key socket in the operating stem for the lock member, and a flywheel of circular cross-section formed on the manipulating key.

35. In a device of the class described, an attaching member for engagement with the frame of a firearm, a blocking member movably mounted on the attaching member and adapted when secured against movement to block firing operation of the firing member, and a lock including a rotary member having a portion adapted to be brought into position to obstruct movement of the blocking member, a shield enclosing the lock to conceal the operative condition thereof from external view, a rotatable operating stem of circular cross-section for the lock member projecting exteriorly from the shield, and a flywheel of circular cross-section adapted to be mounted on the protruding end of the operating stem.

40. In a device of the class described, an attaching member for engagement with the frame of a firearm, a blocking member pivotally mounted on the attaching member and having an end portion adapted to project into the path of movement of the firing member, a hollow cylindrical shield supported by the attaching member and having a slot in its side wall, the end portion of the blocking member opposite to the portion projecting into the path of the firing member being extended through the shield slot into the in-

terior of the shield for angular movement therein, one end of the shield being open, an adjustable cover for the open end of the shield adapted to contact with the inner end of the blocking member to form a stop therefor, and locking means for the blocking member mounted within the shield.

11. In a device of the class described, an attaching member for engagement with the frame of a firearm, a blocking member pivotally mounted on the attaching member and having an end portion adapted to project into the path of movement of the firing member, a hollow cylindrical shield supported by the attaching member and having a slot in its side wall, the end portion of the blocking member opposite to the portion projecting into the path of the firing member being extended through the shield slot into the interior of the shield for angular movement therein, one end of the shield being open, an adjustable cover for the open end of the shield adapted to contact with the inner end of the blocking member to form a stop therefor, and locking means for the blocking member mounted within the shield, and including a rotatable stem projecting exteriorly through the open end of the shield, the shield cover having a bearing opening through which the stem projects, and a disc mounted fixedly on the stem within the shield and having solid portions separated by radial slots adapted to be interchangeably disposed in a position to block or permit free movement of the inner end of the blocking member.

12. A device of the class described comprising an attaching member adapted to be engaged with the frame of a firearm, a chance device movably mounted in the attaching member and adapted to assume any one of a plurality of different positions, means for shielding the chance device to conceal the adjusted position of the same, adjusting means for the chance device externally exposed and being of a construction and movable mounting which will not reveal changes in adjustment, and means controlled by the chance device for locking the firing mechanism of the firearm in one adjusted position of the former and for permitting free operation of the firing mechanism in another position.

13. The combination with a firearm including a frame member and a firing member, of a chance device movably mounted in one of the members and adapted to assume any one of a plurality of different positions, means for shielding the chance device to conceal the adjusted position of the same, adjusting means for the chance device externally exposed and being of a construction and movable mounting which will not reveal changes in adjustment, and means controlled by the chance device for locking the firing member

in one adjusted position of the former and for permitting free operation of the firing member in another position.

14. The combination with a firearm including a frame member and a firing member, of a chance device movably mounted in one of the members and adapted to assume any one of a plurality of different positions, means for shielding the chance device to conceal the adjusted position of the same, an adjusting member for the chance rotatably mounted in the member which bears the chance device and having an exposed manipulating portion of circular cross-section.

In testimony whereof I affix my signature. so
